US0D1067619S

(12) **United States Design Patent** (10) **Patent No.:** **US D1,067,619 S**
(45) **Date of Patent:** **** Mar. 25, 2025**

(54) **CRANK FOR AN UMBRELLA**

(71) Applicant: **Zhejiang Yotrio Group Co., Ltd.,**
Zhejiang (CN)

(72) Inventors: **Youtao Ke**, Zhejiang (CN); **Jincai Hu**,
Zhejiang (CN); **Jianqiang Xie**,
Zhejiang (CN); **Scott Adam Garrison**,
Fitchburg, WI (US); **Corey Lee**,
Pasadena, CA (US)

(73) Assignee: **Zhejiang Yotrio Group Co., Ltd.,**
Zhejiang (CN)

(**) Term: **15 Years**

(21) Appl. No.: **29/962,542**

(22) Filed: **Sep. 12, 2024**

Related U.S. Application Data

(62) Division of application No. 29/856,361, filed on Oct.
13, 2022, now Pat. No. Des. 1,051,585.

(57) **CLAIM**

The ornamental design for a crank for an umbrella, as shown and described.

DESCRIPTION

FIG. 1 is a front perspective view of an embodiment of the crank incorporating the new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 shows the crank installed on an umbrella.

(Continued)

The broken lines depict parts of an umbrella and parts of the crank that form no part of the claimed design.
